UNITED STATES PATENT OFFICE.

JOHN T. RIDDELL, OF EVANSTON, ILLINOIS.

FOOTBALL-PLAYER'S PAD.

Application filed August 11, 1924. Serial No. 731,244.

My invention relates to improvements in football players' pads and has for its object the provision of an improved construction of this character affording a maximum of protection for a football player and at the same time permitting of great freedom of movement. A further object is the provision of such a pad which is of comparatively light weight.

10 Other objects will appear hereinafter.

The invention consists in the combination and arrangement of parts hereinafter described and claimed.

The invention will be best understood by reference to the accompanying drawings forming a part of this specification, and in which:—

Fig. 1 is a front view of a football player's uniform equipped with pads embodying 20 the invention;

Fig. 2 is a rear view of the same;

Fig. 3 is a section through a pad;

Fig. 4 is an enlarged partial view taken on line 4—4 of Fig. 1; and

25 Fig. 5 is a section through another form of pad.

The form of construction illustrated in the drawings comprises a football player's uniform which may, in general, be of any 30 usual or desired construction, the one illustrated being the ordinary "union" suit. Suitable pockets or receptacles 5 are formed in or on this uniform for the reception of the pads for the protection of the player, 35 said pockets being formed at the knees, thighs, hips and sides, shoulder and neck portions thereof as indicated.

Arranged in each of said pockets is a pad for the protection of the corresponding 40 portion of the player's body. In the form of pad illustrated in Fig. 4, each of these pads comprises a soft flexible central core 6 formed of sponge rubber having inflatable cavities therein, said cavities being filled 45 with gas under pressure. The core 6 is covered with a sealing casing 7 also of soft flexible rubber as shown. The core 6—7 is enclosed in a soft flexible inflatable rubber bag 8 and secured in said bag by means 50 of radiating rubber positioning fingers or arms 9 secured to the edges of the core and to the inner walls of the bag as indicated. Each bag is also provided with a suitable inflating nipple 10 of any usual or desired 55 construction whereby the bag may be inflated with air under pressure, thereby fill-

ing the space in the bag around the core 6—7 with air under pressure.

One of the said pads or bags is inserted in each pocket 5 in the uniform 4 and suitably inflated, thus serving to protect the corresponding portion of the body of the player. By this construction, a light weight comparatively flexible protection is provided for the player affording a maximum of protection and freedom of movement. In case one of the bags 8 should become punctured or otherwise deflated, the core 6—7 will in and by itself afford a considerable measure of protection. When the bag is properly inflated this central core gives proper form and stability thereto and also affords protection against unusually severe blows or shocks which might be sufficient to indent the sides of the inflated bag into contact with each other. The effect of the enclosed air or gas under pressure in the bag 8 is to distribute the shock or force of received blows or jars substantially uniformly over the entire bearing surface of the pad and thus prevent injury to the player.

In the form of pad illustrated in Fig. 3 the outer bag 8 is dispensed with entirely and simply the sealing casing or bag 7 filled with the sponge rubber filling body employed. 85 The pad thus formed is inflated by inserting a needle therein in the usual manner for inflating rubber balls and the like, a sealing composition being employed for sealing the puncture formed by the inflating needle. 90 Transverse openings or passages 11 are formed through the pad for ventilating purposes. This form of pad is a very simple construction, capable of economical manufacture and, it is thought, will be generally 95 found to be the preferable form of construction. It is also to be noted that in case of puncture of the outer sealing casing or pad 7 the confined air or other gas will escape but slowly and even after the escape of the 100 confined gas a very efficient pad will be provided due to the effect of the cavities in the sponge rubber filling.

The construction illustrated in Fig. 5 is the same as that illustrated in Fig. 4 except 105 that the central core for the pad has been omitted. This form of construction constitutes a very simple one but, of course, in case of puncture, the pad is almost completely destroyed.

While I have illustrated and described the 110 preferred form of construction for carrying

my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. The combination with a football player's uniform having pockets therein, of a flexible inflatable rubber bag insertable in said pockets; and a soft pad-like filling for said bag, said filling being formed of sponge rubber having minute cavities therein filled with gas under pressure, substantially as described.

2. A football player's pad comprising a flexible inflatable bag, and a soft pad-like filling for said bag, said bag and filling being filled with gas under pressure, and there being transverse ventilating openings extending through said bag and filling, substantially as described.

3. A football player's pad comprising an inflatable rubber casing filled with sponge rubber having minute cavities therein, said casing and said cavities being filled with gas under pressure and said casing being permanently sealed to prevent escape of said gas, there being transverse ventilating openings extending through said casing and filling, substantially as described.

In testimony whereof I have signed my name to this specification.

JOHN T. RIDDELL.
